SILK REELING MACHINE

Gustaf Sigfrid Beckman, Cranston, R. I., assignor
to Universal Winding Company, Boston, Mass.,
a corporation of Massachusetts

Application December 18, 1933, Serial No. 702,984

31 Claims.

(Cl. 19—3)

This invention relates to improvements in filaturing or silk-reeling apparatus and particularly to a machine for automatically supplying silk filaments from cocoons and twisting the strands 5 into a thread which is thereafter reeled into skeins or hanks or wound into other forms.

One object of the invention is to provide a machine or apparatus of the type indicated having means for drawing the filaments from the 10 cocoons, twisting them into a thread and automatically supplying fresh cocoons in accordance with requirements as the filaments from the delivering cocoons become broken or exhausted.

Another object of the invention is to provide 15 a machine of the type indicated having means controlled automatically by the size of the thread being produced to connect fresh filaments therewith as required to maintain uniformity of size in the thread.

Another object of the invention is to provide 20 a machine of the type indicated having automatically-operated means for connecting the filaments from the freshly supplied cocoons to the feeding thread without interrupting the twisting and reeling operations.

Another object of the invention is to provide 25 a machine of the type indicated having means for floating the cocoons in a bath with the liquid circulated and heated to effect degumming of the silk and loosening of the filaments from the cocoons.

Another object of the invention is to provide 30 a machine of the type indicated having means for automatically carrying off or discharging from the bath the depleted cocoons or the larvae residue therefrom.

Another object of the invention is to provide 35 a machine of the type indicated having automatically-actuated means for arresting its operation when the thread breaks.

Another object of the invention is to provide 40 a machine of the type indicated having a plurality of reeling units of compact arrangement adapted for continuous operation from a common source of power.

Another object of the invention is to provide 45 a machine of the type indicated of simple construction, efficient in use for the purpose specified and proof against derangement or getting out of order.

Further objects of the invention are set forth in 50 the following specification which describes a preferred form of construction of the apparatus, by way of example, as illustrated by the accompanying drawings.

In the drawings:

Fig. 1 is an end view of an improved silk-reeling machine constructed in accordance with the present invention;

Fig. 2 is an enlarged part-sectional side view of 5 the machine showing the filament-feeding and cocoon-supplying mechanisms and illustrating the flushing door for the reeling basin opened to permit return of the water to its source of supply and ejection of the spent cocoons;

Fig. 3 is a plan view of one unit of the machine;

Fig. 4 is a sectional view similar to Fig. 2 showing the cocoon-supplying mechanism active 10 to feed a fresh cocoon into location for unwinding 15 its filament;

Fig. 5 is a transverse sectional view of a portion of the reeling basin showing the sluice-gate 20 opened to permit circulation of the water and the passage of the spent cocoons therefrom;

Fig. 6 is a front view of the upper portion of 25 the machine showing two of the winding or reeling units and illustrating the different positions of the various elements of the mechanisms during the reeling and after this operation has been arrested;

Fig. 7 is an end view of the reeling mechanism;

Fig. 8 is a similar end view looking in the opposite direction; and

Fig. 9 is a diagram illustrating the electrical 30 connections for controlling the cocoon-supplying means and the stopping mechanism for arresting the operation of a unit of the machine.

The present improved filaturing or silk-reeling 35 machine comprises, in general, a supply-basin for containing reserve cocoons of raw silk, and a supplemental reeling basin into which the cocoons are fed individually by automatic transferring means and from which location the silk filaments are drawn off from the cocoons. Means 40 are provided for circulating warm emulsion fluid through the two basins to float and degum the cocoons whereby to facilitate the release of the filaments therefrom, together with means for 45 ejecting the denuded cocoons from the reeling basin after their silk becomes exhausted. A take-up device is provided for maintaining the individual filaments taut during the transfer of the cocoons to the reeling basin and a rotary 50 gatherer is employed for selectively grasping the filaments and twisting them about the strands drawing upwardly to the thread being reeled.

Suitable means for winding the spun thread 55 onto a reel or other carrier are arranged above

the basins and a stopping mechanism is provided for arresting the winding or reeling operation when the thread breaks or its supply becomes exhausted. Means for gauging the thickness of the thread as it is spun operate automatically upon breakage or exhaustion of any of the filaments to energize an electrically-controlled cocoon-supplying mechanism to cause a fresh cocoon to be delivered to the reeling basin 10 and its filament joined to the others being twisted whereby to maintain the size or thickness of the thread substantially uniform.

Referring first to Fig. 1 of the drawings, the present improved machine embodies a tray-like tank 2 supported from the floor by legs 3 and serving as a mounting or bed for a plurality of reeling units. With the exception of Fig. 6, the present drawings illustrate only one reeling unit, but it is to be understood that any desired number of similar units may be arranged in series along the length of the bed or tank 2.

Bolted to the offset marginal rim 4 of the tank 2 are cross-struts 5 which bridge its top at spaced intervals therealong. Mounted upon the struts 5 are upright frames 6 which support the winding or reeling mechanisms, to be later described.

Supported upon spaced ribs 8 rising from the bottom of the tank 2 adjacent the forward end thereof is a relatively narrow extended tank or basin 10 which serves as a hopper or container for holding the reserve supply of cocoons c. The basin 10 is fastened in place by means of screws 12 passing through angular sheet-metal feet 13 on its side and screwed into threaded holes in bosses 11 on the bottom of the tank 2. Surrounding an opening 14 in the bottom of the basin 10 is a flange 15 to which is connected a pipe 16. The pipe 16, which serves as the means for supplying water or an emulsion to the basin, extends upwardly through a flanged opening 17 in the bottom of the tank 2, see Fig. 4. As shown in Fig. 1, the pipe 16 is joined to a horizontal pipe 18 extending lengthwise of the machine and connected to a suitable pump, not herein illustrated, which may be supplied with water previously emulsified and heated in a tank or other reservoir. A valve 19 is provided in the pipe 16 for regulating the flow of water to the supply-basin 10.

Within the basin 10 is a raised floor or false-bottom 22 supported on bifurcated legs 23. A series of perforations 24 are provided in the floor 22, see Fig. 3, through which the water is circulated in the manner as indicated by the arrows in Fig. 4. Resting upon the false-bottom 22 are sheet-metal members 25 of triangular shape in plan view, see Fig. 3, with vertical walls converging toward the rearward side of the basin 10. The rearward wall of the basin 10 is formed with a rectangular opening 26 which registers with the narrower end of the space between the walls of the members 25. As before explained, the water enters the upper portion of the basin 10 through the apertures 24 in the false-bottom 22 and the sides of the members 25 may also be perforated to adapt the water to debouch therefrom to set up a current tending toward the opening 26 whereby to float the cocoons therethrough. It will be understood that a plurality of members 25 are provided along the length of the basin 10 arranged in spaced relationship to partition its interior into substantially funnel-shaped compartments, one for each reeling unit.

Resting upon bosses on the bottom of the tank 2 are a series of tanks or basins 30, each dis-

posed opposite one of the openings 26 in the rearward side of the supply-basin 10 and extending nearly to the opposite rearward side of the tank 2. Each basin or tank 30 is of rectangular shape with its interior divided into a number of compartments as later described. The forward end of each basin 30 is provided with angular sheet-metal ears 31 riveted to the rearward side of the basin 10, as shown in Fig. 3, while at its opposite end are feet 32 screwed to bosses on the bottom of the tank 2, see Fig. 2.

Substantially midway of the ends of the tank 30 is a separator-plate or partition 33 having lateral ears 34 at its ends riveted to the sides of the tank. The compartment 35 thus provided has at its forward end an opening 36 which registers with the opening 26 in the rearward side of the basin 10 to permit the fluid and cocoons to pass therethrough into the compartment.

At the rear of the partition 33 is a shelf-like frame 38, see Fig. 4, having an inclined wall 39 provided with lugs 40 fastened to the partition. From the inclined wall 39 the shelf or frame 38 reaches rearwardly and then downwardly to terminate in a forwardly extending foot 41 screwed to the bottom of the tank 30. By this construction a laterally-extending chamber 42 is formed in the tank 30 into which water may be introduced by way of an inlet pipe 43. As shown in Figs. 3 and 4, a series of perforations 44 are provided in the inclined wall 39 through which the water may pass to the reeling basin, indicated generally by the reference character 45, located thereabove. The pipe 43 extends through an opening 46 in the tank 2 and is connected to a flange 47 surrounding an opening in the bottom of the tank 30 which registers with an opening 48 in the foot 41 of the frame 38. The pipe 43 leads from the pipe 16, previously mentioned, and a valve 49 is provided in the line for regulating the rate of flow of water to the reeling basin 45, see Fig. 1.

Fastened to the shelf-portion of the frame 38 is a plate 50 which slopes downwardly toward the rearward end of the tank 30. Adjacent its rearward end the plate 50 is provided with a horizontal foot 51 which rests upon the floor of the tank 30 and is formed with a rectangular aperture 52. The plate 50 has an upright extension 53 disposed in spaced relation to the rearward wall of the tank 30, forming therewith an overflow passage 54 for the return of the water to the heating apparatus through an opening 55 in the bottom of the tank 30. The upright portion 53 of the plate 50 may be secured to the sides of the tank 30 by means of bolts 56.

The section of the tank 30 located above the plate 50 is divided into two compartments by a gate 57 slideable in guideways 58 formed in strips 59 riveted to the sides of the tank 30. The forward compartment 45 of the tank 30 constitutes the reeling basin, so-called because the filaments are drawn off from the cocoons floating therein, while at the rearward side of the gate 57 is a flushing chamber 60. The opening 52 in the bottom of the flushing chamber 60 is normally closed by a trap-door 62 which is operated by cam-actuated means, to be later described, to cause it to be periodically opened to discharge the water from the chamber 60. Beneath the opening 52 is a funnel-shaped discharge duct 63 fastened to the bottom of the tank 30 and connected by a suitable pipe to the tank in which the water is heated. The means for feeding fresh cocoons 75

into the reeling basin 45 is constructed and arranged as next described.

Referring particularly to Figs. 3 and 4, a pair of hinge-blocks 65 fastened to the forward wall 5 of the tank 30 carry hinge-pins 66 upon which is pivotally mounted a rockable raceway member 70. The member 70 is of channel or trough shape comprising a flat bottom 68 and upstanding sides 69. At the forward end of the member 70 are 10 guide-members 71 having vertical walls which converge rearwardly in alignment with the angular walls of the members 25 in the basin 10, thereby providing a reentrant opening or mouth for receiving the cocoons as they are floated 15 through the opening 26 and into the basin 35. Fastened to the bottom and sides of the member 70 are angle-shaped members 72 which form a restricted passage or raceway 73 extending longitudinally of the member from its mouth to its 20 rearward end, see Fig. 3.

Depending from the bottom of the member 70 are a pair of spaced bearing lugs 74 between which is journaled a roller 75. The roller 75 is engaged with the periphery of a lenticularly-shaped cam 76 fast on a shaft 77 extending transversely of the interior of the tank 30. The cam 76 is connected to be rotated, by means as later described, to alternately raise and lower the raceway member 70 on its pivot to assist in feeding the cocoons to the reeling basin 45. The bottom wall of the member 70 is slotted to receive a feeding or transferring element 80 which is slidably mounted on a transverse pin 81 extending between lugs 82 at the rear of the member.

The feeding element 80 is of bucket-like construction having a bottom and inclined side walls. On the bottom of the element 80 are spaced flanges 83 formed with elongated slots 84 for receiving the hinge-pin 81. A pivot-pin 85 extending between spaced ears on a plate 86 fastened to the partition wall 33 also passes through the slots 84 in opposite relation to the pin 81. The bucket 80 is thus held suspended while permitting it to pivot and slide within limits as determined by the ends of the slots 84. The bucket 80 is normally maintained in inclined position facing toward the raceway 73 in the member 70 as shown in Figs. 2 and 3 to adapt the foremost cocoon c passing through the runway to enter into its cavity.

When a fresh cocoon is to be fed into the reeling basin 45 the cam 76 is rotated to rock the raceway member 70 upwardly as shown in Fig. 4. This movement of the member 70 causes the pivot-pin 81 to ride along the slots 84 of the bucket 80 to swing the latter about its hingepin 85. The oscillating movement of the bucket 80 is relatively rapid whereby it acts to lift the foremost cocoon in the series and project it into the reeling basin 45 where its filament is joined to the other filaments being twisted into the thread by the operation of instrumentalities to be later described. As a means for preventing the next cocoon in the series from passing into the end of the raceway 73 during the transferring operation a flap-like guard or gate 87 is provided on the bucket 80. The gate 87 is suspended on a pin 88 extending transversely of the feeding bucket 80 with its lower curved end adapted to ride on the arcuately-shaped side of a standard 89 rising from the floor of the tank 30.

In addition to actuating the feeding bucket 80 the member 70 also functions during its oscillating movement to cause the cocoons to advance toward its delivering end. Pivoted to the

upper forked end of a bracket 90 fastened to the bottom of the tank 30 is a weighted lever 92 constituted as an agitator for the cocoons. The bracket 90 projects upwardly through a relatively wide rectangular aperture in the bottom of the member 70 and the weighted end of the agitator lever 92 projects downwardly through a narrower aperture. The mid-portion of the lever 92 is thus arranged to rest upon the narrow strip 93 of the bottom of the member 70 which separates the two apertures. With the member 70 at rest in horizontal position as shown in Fig. 2 the lever 92 is positioned below the cocoons c floating in the raceway. When the member 70 is raised, however, the cross-strip 93 engages with the under side of the lever 92 and causes it to pivot upwardly as illustrated in Fig. 4. The end of the lever 92 will thus act to lift the cocoons gathered in the mouth of the raceway 73 to cause them to be agitated, whereby to prevent them from clinging and bunching together to clog the entrance.

Rising from the floor of the tank 30 within the basin 35 is an overflow-tube 94 for maintaining a constant level in the basin. The water passes 25 downwardly through the tube 94 and into the tank 2, from which it exhausts through a return-pipe 95 leading to the heating apparatus. As a means for regulating the return flow of water a valve may be provided in the upper end of the 30 tube 94. A plug 96 screwed into the end of the tube 94 is provided with a hole in its side adapted to register with a similar hole in the side of the tube. By turning the plug the size of the valve opening may be varied to change the rate of 35 flow to maintain the proper level of the water in the supply and runway basins 10 and 35. In the bottom of the basin 35 is a small hole 97, see Fig. 4, which permits the water to drain therefrom when the reeling unit remains idle for any considerable period.

Attached to the frame 6 above the basin 35 is a bracket 99, in which is journaled two shafts 100 and 101, see Figs. 2 and 4. The lower shaft 100 has fixedly secured thereto a spur-gear 102 which meshes with a similar gear 103 on the shaft 101. The shaft 100 also carries a sprocket 104 which is driven by a chain connected to a sprocket 105 on the cam-shaft 77, previously mentioned. The upper shaft 101 carries a take-up element 106 comprising a hub with a pair of arms 107 radiating therefrom. At the ends of the arms 107 are fingers 108 to which the individual silk filaments from the reserve cocoons in the supply basin 10 and raceway 73 may be 55 manually attached. During the feeding or transferring operation the take-up element 106 is rotated to wind up the several filaments attached thereto to take up any slack therein. Projecting from the side of the bracket 99 is an arm 109, 60 to the end of which is fastened a baffle or guard-plate 110 for preventing the loose end of a filament attached to the take-up element 106 from catching on and becoming entangled with the multiple strands passing upwardly to the reeling 65 mechanism.

The drive for the several operating mechanisms of the different units of the apparatus is arranged as next described. Referring particularly to Figs. 1 and 3, a main drive-shaft 112 is 70 journaled in a bearing 113 at the end of the tank 2 and in an outboard bearing 114 formed at the end of a bracket 115 bolted to the side of the tank. At the outer end of the shaft 112 is a pulley 116 which may be connected by a belt to an 75

electric motor or any other suitable source of power. Keyed to the shaft 112 is a second pulley 117 which drives the reeling mechanism, to be later described, by means of a belt 118. Fixedly secured to the shaft 112 is a worm 119 which meshes with a worm-wheel 120 fast on a shaft 121 extending beneath the shaft 112 at right-angles thereto. The shaft 121 is journaled in a bearing 122 forming part of the bracket 115 and in another bracket 123 on the side of the tank 2. The shaft 121 projects beyond the end of the bearing 123 and carries a spiral gear 126 which meshes with a larger spiral gear 127 fast on the end of a cam-shaft 128. The cam-shaft 128 extends horizontally within the tank 2, being journaled in bearing bosses at the ends thereof. The cam-shaft 128, which is driven at a relatively slow rate of speed, constitutes the means for operating the sluice-gate 57 and flushing door 62 as will be presently explained. The drive-shaft 112 has keyed thereto a sprocket 130 which is connected by a chain 131 to drive a larger sprocket 132 fast on the end of a shaft 133 arranged above the cam-shaft 128 in parallel relation thereto and constituting the driving means for the cocoon feeding mechanism. The two shafts 128 and 133 may also be journaled in other bearings supported by brackets 134 arranged in spaced relation within the tank 2.

30 The sluice-gate 57, previously mentioned, consists in a rectangular plate having its upper edge slotted to provide openings through which the water normally flows from the reeling compartment 45 into the flushing chamber 60, see Figs. 3 and 4. A series of small holes 135 are provided near the bottom of the gate 57 to adapt the water to continuously circulate therethrough to exert a slight pull or drag on the cocoons in resistance to the draft on the filaments delivering therefrom. The gate 57 is provided with a rectangular slot 136 which is engaged by the forward end of a lever 137. The lever 137 is fast upon a shaft 138 extending along the rearward wall of the tank 30 and journaled in bearing blocks 139 screwed thereto. The lever 137 is formed with a depending toe 140 adapted to strike against one of the bearing blocks 139 to limit the upward swinging movement of the lever. Fast on the shaft 138 is a lever 141 having a rearwardly-directed curved arm 142 and an upwardly extending arm 143. The end of the curved arm 142 is maintained in engagement with the periphery of a cam 144, fast on the cam-shaft 128, by means of a spring 145. One end of the spring 145 is anchored to one of the studs 56, previously referred to, while its opposite end is hooked around a pin driven into the side of the arm 142. The cam 144 has a peripheral contour of substantially segmental shape. With the segmental portion of the cam 144 in the position shown in Fig. 4 the arm 142 of the lever 141 is held raised to maintain the lever 137 depressed with the gate 57 closed down against the bottom of the reeling basin. When the cam 144 is rotated in clockwise direction, as viewed in Fig. 5, its segmental portion rides out from under the curved arm 142 of the lever 141 and the rod 138 will be rotated under the action of the spring 145 to cause the lever 137 and gate 57 to be raised to the position shown in Fig. 5; the toe 140 on the lever 137 bringing up against the end of the tank or basin 30 to limit the movement of the lever 137. The water then flows rapidly from the reeling basin 45 to discharge the spent cocoons into the flushing chamber 60 whence they are

subsequently ejected by the means previously described.

Journalized in bearings on the sides of the tank 30 is a shaft 146 upon one end of which a handlever 147 is rotatably mounted. Hooked around the lever 147 and resting on a pin 148 projecting from its sides is a wire link 149, the opposite end of which is hooked through a hole in the upper arm 143 of the lever 141, see Figs. 3 and 4. Fastened to the side of the lever 147 is a spring-finger or latch 150 which is adapted to snap into one or the other of two slots 151 and 152 in the overhanging rim of the tank 30, see Fig. 3. During the normal operation of the reeling unit the lever 147 is tilted to the right as viewed in Figs. 2 and 3 with its spring-finger 150 held in the slot 152. As the lever 141 is rocked from the cam 144 in the manner as before explained the link 149 slides back and forth upon the pin 148 in the lever 147. On the other hand, the lever 147 may be manually rocked toward the front of the machine to draw the link 149 forwardly to elevate the curved arm 142 of the lever 141 to the position indicated by the dash lines in Fig. 5. The purpose of this arrangement is to render the gate-operating mechanism inoperative whereby to maintain the gate 57 closed against the bottom of the basin. The lever 147 is held in its forward position by the engagement of its latch 150 with the slot 151. The object of holding 30 the gate 57 closed is to aid the operator in starting the reeling unit, for if the gate 57 were permitted to open during the threading up of the filaments the rapid circulation of the water through the reeling basin would float the cocoons 35 into the flushing chamber 60. After the filaments have been connected to the reeling mechanism and the latter started to operate to take up the thread the draft on the strands holds the cocoons in the reeling basin 45 and the lever 147 40 may be returned to first position as shown in Figs. 2 and 4 to release the lever 141 for engagement by the cam 144 to intermittently operate the gate 57.

The cam-shaft 128 carries fast thereon a cam 45 154, see Fig. 2, for operating the flushing door 62. The cam 154 is constructed in the form of a circular disk having a substantially V-shaped notch 155 in its periphery. A lever 156 having a slotted end 157 engaging around the cam-shaft 128 carries a roller 160 adapted to ride on the periphery of the cam 154 and to enter its notch 155. The forward end of the lever 156 is pivotally connected to the upper end of a crank-arm 161 fast on the end of a rod 162 journaled in bearings on 50 the sides of the tank 30 and constituting the pivot for the flushing door 62, previously mentioned. The door 62 consists in a rectangular plate provided with perforated ears 163 hinged on the rod 162. Fast on the rod 162 midway between the hinge-ears of the door 62 is a lifter member 164 which reaches downwardly beneath the door 62 and carries a forked leaf-spring 165 for engaging against the under side thereof. When the rod 162 is rocked in contraclockwise direction, as viewed in Fig. 2, the lifter member 164 acts through its spring 165 to resiliently maintain the door 62 against the bottom of the plate 50 to close the opening 52 therein. To prevent leakage around the opening 52 the door 62 may carry a suitable gasket cemented thereto.

When the cam 154 is turned to the position indicated by the dash lines in Fig. 5 the lever 156 is moved forwardly to cause the lifter member 164 to hold the door closed against the bot- 75

tom of the flushing chamber 60. On the other hand, when the cam 154 is turned to the position illustrated in Fig. 2 with its notch 155 opposite the roll 60 the lever 156 will be free to slide to the right to permit the lifter 164 to be lowered by the weight of the door 62 and the pressure of the water thereagainst. In other words, the turning of the cam releases the lever 156 so that the crank-arm 161 may rotate to the right as viewed in Fig. 2 under the pressure of the door 62 against the lifter 164. The release of the door 62 results in rapid exhaust of the water from the basin 30 to carry the spent cocoons down into the waste pipe 63.

15 As previously noted, the cocoon feeding and filament take-up means for the reeling unit are operated from the shaft 77 extending transversely of the tank 30. At one end of the shaft 77 is a clutch-device, indicated generally in Fig. 3 by the reference character 168, comprising a disk 169 fast with the shaft 77 and a cup member 170 rotatable thereon. The two clutch members 169 and 170 are frictionally engaged to adapt them to rotate as a unit, but the member 169 and thereby the shaft 77 are normally held against rotation by means of a detent-lever 171, shown most clearly in Fig. 2. The member 170 which is free on the shaft 77 carries a sprocket 172 driven by a chain 174 connecting it to a sprocket 173 on the shaft 133.

30 The detent-lever 171 is fast on the shaft 146, being formed at one side with a detent-lug 176 which engages a projection 177 on the periphery of the clutch member 169 to withhold the latter from rotation. The lever 171 is normally held in upright position with its lug 176 engaged with the projection 177 by means of a weighted arm 178 fastened to the rod 146 and tending to rotate the latter in clockwise direction as viewed in Fig. 40 2. A knock-off lever 180 formed with a double-sided end is pivotally connected to the lever 171 by means of a pin 179, see Figs. 2 and 3. Fasted to the shorter end of the lever 180 is a counterweight 181. The counterweight 181 45 maintains the lever 180 in substantially horizontal position as illustrated in Fig. 2 with its longer arm extending to the right to locate its extremity in advance of and below the axis of a toothed wheel 182 carried on and continuously 50 rotated by the shaft 133. The longer or right-hand end of the lever 180 is guided in a vertical slot formed in a bracket 183 riveted to the side of the tank 30.

55 Mounted on an angular bracket 184 fastened to the side of the tank 30 and suitably insulated therefrom are two electromagnets 185 which are connected by a conductor 186 to the automatic detector or sizing device to be later described. The detector device is designed to operate on the 60 thread being reeled to detect the absence of the required number of strands and to energize the magnets 185 from a suitable source of electric current. The magnets 185 are thereby caused to attract the weight 181, which constitutes an 65 armature on the lever 180, to rock the latter to raise its rearward end into position to be engaged by the teeth of the wheel 182. The wheel 182 rotates in the direction indicated by the arrow in Fig. 2 and as the knock-off lever 180 is 70 engaged with one of its teeth it pushes the lever to the left, as viewed in Fig. 2, to rock the detent-lever 171 whereby to free its detent-lug 176 from the projection 177 on the clutch member 169. As the clutch member 169 is released its companion 75 member 170 causes it to be rotated to turn the

shaft 77. The rotation of the shaft 77 initiates the operation of the cocoon feeding and filament take-up devices in the manner and for the purposes as later more fully explained.

Means are provided for joining the filament from a newly supplied cocoon to the multiple filaments being reeled as each fresh cocoon is fed into the reeling basin. Referring to Figs. 1, 2 and 4, the filament-connecting means or gatherer is carried on a bracket 187 bolted to the top of one of the cross-struts 5 overlying the tank 2 and also to one of the upright frames 6. Journaled in a bearing 188 at the forward end of the bracket 187 is a hollow or tubular spindle 189 carrying a grooved pulley 190 at its lower end. 15 A nut 191 screwed against a shoulder on the spindle 189 cooperates with the pulley 190 abutting the lower end of the bearing 188 to retain the spindle in place. Secured to the under side of the pulley 190 is a rotary gatherer 192 20 constituted by a pair of opposite arms 193 radiating from a central hub. Secured within the ends of the hollow spindle 189 are porcelain guide-eyes 194 through which the filaments draw as they lead upwardly to the reeling mechanism. The 25 gatherer 192 is continuously rotated at a relatively high rate of speed by means of a belt 197 passing around the pulley 190 and connected to a larger pulley 196. The pulley 196 is mounted on the upper end of a vertical shaft 198 journaled in a bearing in a bracket 199 rising from the bottom of the tank 2. Secured fast on the shaft 198 is a spiral gear 200 which meshes with a larger spiral gear 202 fast on the shaft 133. 30

Through the connections last described the 35 gatherer 192 is rotated to cause one or the other of its arms to engage the filament from the cocoon being fed to the reeling basin 45 in the manner as illustrated in Fig. 4 and to twist the strand around the other filaments drawing upwardly through the shaft 189.

40 A scraper 205 is provided for removing the water and any foreign matter adhering to the filaments as they are drawn upwardly from the reeling basin 45. As shown in Figs. 2 and 4 the scraper 205 is carried at the end of a swinging arm 206 pivoted between the sides of a U-shaped bracket 207 secured to the bracket 187. As shown in Fig. 3 the scraper 205 consists of a 45 length of wire bent to form opposite parallel legs 208 defining a restricted passage through which the filaments draw. The legs 208 are extended forwardly and upwardly to provide a reentrant throat for guiding the filaments into the scraper opening between the legs. The scraper 205 is arranged to swing out of the way as each fresh cocoon is fed into the reeling basin 45 to prevent it from interfering with the transferring operation. For this purpose the arm 206 is connected by a wire link 209 to an upwardly projecting ear 210 on the cocoon-feeding bucket 80. As the bucket 80 is oscillated during the feeding operation the link 209 moves the scraper 205 back to the position illustrated in Fig. 4 so that the cocoon being transferred may enter the basin 45 without interference. As the feeding element 80 returns to first position it draws the scraper 205 forwardly into the position shown in Fig. 2, whereby the filaments being drawn from the cocoons are automatically gathered into its restricted opening. 50

55 From the guide-eye 194 of the gatherer spindle 189 the multiple strands draw upwardly over a pulley 212, see Fig. 1, which is carried at the end of an arm 213 pivoted on a pin 214 projecting 60

from a bracket 215 secured to the front of the upright frame 6. From the pulley 212 the strands lead downwardly around a pulley 217 journaled on the frame 6 and thence upwardly, 5 being twisted numerous times around the strands drawing upwardly from the gatherer to the pulley 212. The twisting of the strands in this manner causes them to be spun into a thread *t* which is led over a roller 219, see Figs. 7 and 8. The roller 10 219 is fast on a shaft 220 journaled in the bracket 215 and carries a pulley or sprocket wheel 221 which is connected by a chain 224 to a sprocket 222 on the drum-shaft 272 of the reeling mechanism. The outer end of the shaft 220 is journaled in an outboard bearing 225 secured to the side of the bracket 215, see Fig. 6.

Slidably mounted in a bearing 226 located beneath the roller 219 is a scraper-blade 227 having a beveled upper edge. The blade 227 is normally urged upwardly to maintain its beveled edge in engagement with the bottom of the roller 219 by means of a coil spring 228 anchored to a pin driven into the side of the bearing 225. The blade 227 serves as a means for removing water 25 and scraping foreign matter from the roller 219 to maintain the latter clean.

Pivoted upon a pin 229 located above the roller 219 is a detector element 230. The pivot-pin 229 is held between the sides of a bifurcated member 231 adjustably mounted upon a bracket 232 screwed to the side of the bracket 215. The detector 230 consists in an arm 223 pivoted on the pin 229 and inclined downwardly toward the roller 219. The lower portion of the arm 223 is bent upwardly at right-angles, thus forming a ridge or shoulder 236 which rests upon the top of the roller 219, and then continued in a horizontal arm 235. The member 230 may be held raised on its pivot by means of a detent-lever 237 whereby to render the detector device and cocoon-feeding mechanism inactive when it is desired to operate the machine while manually feeding cocoons to the reeling basin. The detent-lever 237 is pivoted on the bracket 231 and provided with an arm 238 adapted to be rocked downwardly to engage the upper end of the arm 223 of the detector 230 to maintain its horizontal arm 235 raised.

At the forward extremity of the horizontal arm 235 of the detector 230 is a contact-point 239 adapted to close against a similar contact-point 240 on a stationary blade 241. The blade 241 is held in the slotted end of a pin 242 driven into the side of the bracket 215 and extends laterally therefrom beneath the arm 235 of the detector 230. Engaging under the end of the blade 241 is an adjusting screw 243 threaded through a split bearing 244 on the bracket 215. A binder-screw 245 in the split bearing 244 may be tightened to clamp the screw 243 in adjusted position with the contact-point 240 spaced at the proper distance from the point 239. The space between the contact-points 239 and 240 is adjusted to equal substantially the thickness of one of the individual filaments of the thread *t* being reeled so that should a filament break or become exhausted the resultant reduction in the size of the thread will cause the detector element 230 to be lowered to bring its contact-point 239 into engagement with the point 240.

Referring now to the electrical diagram in Fig. 9, the contact-point 239 is connected by the wire 186 to the magnets 185, previously described, and the stationary contact-point 240 is connected 75 to a wire 248 in circuit with the source of electri-

cal current. When the circuit is closed at the contact-points 239 and 240 the current flows to the magnets 185 to energize the latter and operate the mechanism which feeds a fresh cocoon into the reeling basin to replace a spent one. As the filament from the fresh cocoon is incorporated into the thread being reeled it eventually increases the size of the thread at the roller 219 and the detector element 230 is raised to open the circuit. 10

From the roller 219 the thread *t* draws around a grooved pulley 250 rotatably mounted at the forward end of a wire arm 251, see Fig. 7. The rearward end of the arm 251 is doubled around to straddle the reduced end of a shaft 252, to 15 which it is adjustably secured by a nut 253. The shaft 252 is journaled in a bearing in the bracket 215. The pivotal movement of the arm 251 and shaft 252 is limited by a stop-pin 254 driven into the side of the bracket 215 and engageable with 20 the sides of the double end of the arm.

At the opposite side of the bracket 215 the shaft 252 carries a collar 255 having a pin 256 projecting radially from its periphery. Mounted on a shelf-like bracket 257 attached to the 25 bracket 215 are two contact-blades 258 and 259 constructed of spring metal and suitably insulated from each other. The blades 258 and 259 are provided with contact-points for closing another circuit which controls the stopping 30 mechanism for the machine in the manner as later explained. Breaking of the thread *t* between the roller 219 and the reeling mechanism causes the pulley 250 to drop to turn the shaft 252 and through the pin 256 the contact-blade 35 258 is carried against the blade 259 to close the circuit.

The arm 213, previously described as carrying the pulley 212, is formed with a rearward extension 260 which is bent upwardly and provided 40 with a rounded end 261 arranged to overlie the upper contact-blade 258. The extension 260 carries a weight 262, see Fig. 8, which tends to depress its rounded end 261 when the strands break at a point between the reeling basin and the detector whereby to move the contact-blade 258 45 against the blade 259.

The winding or reeling mechanism for taking up the twisted thread may be of any suitable type and is therefore described only briefly herein in 50 its relation to the operation of the complete machine. Referring particularly to Figs. 6, 7 and 8 a pair of spaced arms 265 are pivotally supported upon a rod 266 extending through suitable bearings at the upper ends of the frame-members 6. 55 At their forward ends the arms 265 carry a spindle 267 upon which may be mounted a reel 268 for receiving the thread, or in other cases a spool or the like. The reel 268 herein illustrated is secured to the spindle 267 by suitable means 60 such as a thumb-screw 269 in its hub engaging a squared portion of the spindle. Adjacent one of the arms 265 the spindle 267 carries a traction wheel or roller 270 adapted to rest upon the periphery of a driving drum 271 to be frictionally 65 driven thereby during the reeling operation and removed therefrom to arrest the winding. The drum 271 is fast upon a shaft 272 extending horizontally through bearings in the frames 6. The shaft 272 is extended at one end of the machine 70 to receive a pulley 273, see Figs. 1 and 6, which is continuously rotated from the drive-pulley 118, previously referred to.

Supported from the end frame 6 of the series is a stud-shaft 274, see Fig. 6, upon which is rotat- 75

ably mounted a traverse-cam 275. A spur-gear 276 on the hub of the cam 275 meshes with a similar gear 277 fast on the drum-shaft 272 whereby the cam is driven continuously therefrom. Extending longitudinally of the whole series of units of the machine is a reciprocable traverse-rod 278 which carries a plurality of thread-guides 279, one for each reeling unit. The traverse-rod 278 is slidably supported between 10 pairs of rollers 280 journaled on brackets 281 projecting forwardly from the frames 6. At one end of the traverse-rod 278 is a roll or bowl 282 engaging in the groove 283 of the cam 275. The thread *t* leads upwardly from the pulley 250 15 through a groove in its appropriate thread-guide 279 and thence to the reel 268. As the traverse-rod 278 is reciprocated from the cam 275 the thread-guide 279 traverses the thread back and forth to deposit it on the reel in coils which form 20 the skein indicated at S.

The stopping mechanism for arresting the reeling operation when the thread breaks is arranged as next described. Rockably mounted in lugs 284 on one of the arms 265 is a lifter rod 285 shaped 25 with its forward end extending downwardly in a leg 286, see Fig. 6. Fast on the drum-shaft 272 is an eccentric disk 287 the periphery of which is adapted to engage the end of the leg 286 to swing the arm 265 upwardly to raise the roller 270 away 30 from the driving drum 271. The arm 265 may be held in its elevated position by means of a latch 288 pivoted at 289 to a lug on the arm 265 with its end bearing against a detent-plate 290 arranged for vertical adjustment on the frame-member 6. 35 The latch 288 has a forwardly extending arm or handle 291, the weight of which tends to hold the latch 288 against the detent-plate 290. When the arm 265 is raised the latch 288 rides upwardly and engages over the edge of the plate 290 to hold 40 the arm in elevated position. When it is desired to start the winding the handle 291 on the latch 288 is raised to permit the arm 265 to descend to carry the roll 270 into peripheral contact with the driving drum 271.

45 The rearward end of the arm 265 is formed with a lateral curved projection 293, to which is fastened a sheet-metal holder 294 for supporting a pair of electro-magnets 295, see Figs. 6, 7 and 8. Referring to the diagram in Fig. 9, the poles of 50 the magnets 295 are connected to the contact-blade 258 by a wire 292, while their windings are connected to the main ground wire 308 of the electrical circuit. Fastened to the rearward end of the lifter rod 285 is a sheet-metal finger 296 55 which extends horizontally beneath the cores of the magnets 295. The weight of the finger 296 tends to normally turn the rod 285 in a clockwise direction, as viewed in Fig. 6, to maintain its leg 286 free from engagement with the eccentric disk 287 as indicated in the showing of the right-hand reeling unit of this view. Energization of the 60 magnets 295 will lift the finger 296 to rock the rod 285 to swing its leg 286 into position to be engaged by the periphery of the eccentric 287 in the manner as illustrated in the showing of the 65 left-hand reeling unit in Fig. 6. The downward movement of the finger 296 is limited by the curved end of an arm 306 fastened at its upper end to the curved projection 293 on the arm 265.

70 Pivoted on a pin 298 projecting from the frame-member 6 is a holder 299 carrying a mercury switch 300. The switch 300 is of usual form comprising a hermetically sealed glass tube 301 enclosing two spaced contact-members 302 and 303. 75 The contact-members 302 and 303 are connected

to wires 304 and 305 in circuit, respectively, with the source of electrical current and leading to the contact-blade 259, see Fig. 9. The holder 299 has an upstanding finger 310 at its pivoted end adapted to engage with the bottom edge of one of the reel-supporting arms 265. During the reeling operation the arm 265 is engaged with the finger 310 on the holder 299 to maintain the switch 300 in the position indicated in Figs. 7 and 9 with the mercury in the tube 301 closing the 10 gap between the contacts 302 and 303. When the thread being reeled breaks the blade 258 is lowered against the blade 259 to cause the current to flow to the magnets 295 to energize the latter and effect stopping of the winding operation in 15 the manner as before indicated. As before noted, the arm 265 is raised to arrest the winding operation and as it is swung upwardly the switch 300 is permitted to swing downwardly to the position shown in Fig. 8. The tilting of the switch 300 20 causes the mercury to flow to the lower end of the tube 301 to open the gap between the contacts 302 and 303 whereby to interrupt the main circuit to prevent continuous feeding of fresh cocoons to the reeling basin under the action of 25 the detector device.

Referring to Fig. 9, the current line comprises two conductors 307 and 308 which may be enclosed in a conduit-pipe 309 extending the length of the machine and held in bosses on the frame-members 6. The various mechanisms of the machine having now been described in detail their method of operation will next be explained.

The individual reeling units are prepared for operation by first opening the valves 19 and 49 35 to supply the basins 10 and 45 with warm emulsified fluid, the flow of which is regulated by the proper adjustment of the valves. A reserve supply of silk cocoons *c*, previously prepared by boiling and brushing, are placed in the supply basin 40 10 and their filaments drawn upwardly to the take-up device 106 and fastened to the fingers 108. The required number of cocoons are placed in the reeling basin 45 with the ends of their filaments gathered together and threaded upwardly 45 through the tubular spindle 189 of the gatherer 192, a suitable threading needle or like implement being used for this purpose. During the threading-up of the filaments the lever 147 is rocked to move the link 149 to close the gate 57, whereby 50 to prevent the cocoons from being floated out of the reeling basin 45 into the flushing chamber 60. As the lever 147 is shifted for this purpose its spring-finger or latch 150 snaps into the notch 151 to lock it in position. 55

The number of cocoons in the reeling basin 45 is determinate upon the number of strands required for a given size of thread, five filaments being herein shown delivering to the reeling mechanism as an example. After passing 60 through the gatherer spindle 189 the multiple strands are drawn upwardly over the pulley 212, thence downwardly around the pulley 217 and led upwardly again and coiled or twisted about the first length drawing upwardly to the pulley 212. 65 The strands are then led over the roller 219, under the pulley 250 and thence drawn upwardly through the groove in the thread-guide 279 with the ends joined to the reel 268 by winding them several times therearound. The reeling unit is 70 then ready for operation.

To start the reeling operation the lever 291 is lifted to disengage its latch 288 from the detent-plate 290 whereby to permit the arms 265 to swing downwardly to engage the drive-wheel 75

270 on the reel-spindle 267 with the rotating driving drum 271, see Figs. 7 and 8. Immediately the roll 270 contacts with the drum 271 it is driven therefrom to turn the reel 268 to wind on the thread *t*. Concurrently therewith the traverse-bar 278 is reciprocated from the cam 275 to impart a traverse to the thread as it feeds through the guide 279. As the reel-carrying arms 265 are lowered the switch 300 is caused to be tilted to the position indicated in Figs. 7 and 9 to connect the detector device in circuit with the source of current.

As soon as the winding or reeling operation is started the operator shifts the lever 147 to release the gate-lever 141, see Fig. 5, for engagement of its arm 142 with the cam 144. As the cam 144 is continuously rotated it acts to periodically raise and lower the gate 57 to cause the water in the reeling basin 45 to flow into the flushing chamber 60. After each closing movement of the gate 57 the cam 154 comes into position to permit the roll 160 on the lever 156, see Fig. 2, to enter its notch 155 whereby the flushing door 62 is swung open to release the water in the chamber 60. The water is thus permitted to return to the supply-tank to be reheated and again circulated through the basins 45 and 60. During the period in which the gate 57 is opened the water rises first in the compartment 60 and then in compartment 45 until it finally overflows into the opening 54 as indicated by the broken lines in Fig. 5. During the operation of the water-flow controlling means the filaments continue to be drawn off from the floating cocoons in the basin 45 regardless of the depth of the water therein.

The reeling operation continues in the manner explained until a fault or breakage occurs in the thread *t* being reeled. When one of the individual filaments breaks or its supply from the cocoon is exhausted the thickness of the thread is reduced so that the detector 230, see Fig. 7, is lowered slightly to cause its contact-point 239 to make contact with the fixed contact-point 240. The electrical circuit to the feed-magnets 185 is then closed and the magnets energized to exert a downward pull on the weighted end 181 of the knock-off lever 180, see Figs. 2 and 9. The rearward end of the lever 180 is thus raised to engage it with one of the teeth of the knock-off wheel 182 which acts to slide the lever to the left as viewed in Fig. 2. The sliding movement of the lever 180 rocks the clutch-lever 171 to the left, as viewed in Fig. 2, to free its lug 176 from the projection 177 on the clutch-member 169, thereby by releasing the latter for rotation by frictional contact with its constantly rotating companion member 170. As before noted, the clutch-member 169 is keyed to the cam-shaft 77 to impart rotation to the latter. The rotation of the cam-shaft 77 turns the cam 76 to cause it to act through the roller 75 to tilt the raceway-member 70 upwardly to the position illustrated in Fig. 4. This rocking motion of the raceway-member 70 is communicated to the cocoon-feeding bucket 80 to tilt the latter on its pivot 85 in the manner as before indicated to project a fresh cocoon into the reeling basin 45. At the same time the agitator-lever 92 is caused to jump upwardly to dislodge any of the cocoons which may have clung together to clog the mouth of the raceway 73.

During the transfer of the fresh cocoon into the reeling basin 45 the take-up device 106 is operated from the shaft 77 to wind up the filament to maintain it taut. Concurrently with this operation the take-up 106 winds up the

other filaments attached thereto to draw the cocoons along the raceway 73 to advance the leading one into position against the stop member or gate 81, see Fig. 4. Now, as the member 70 is rocked downwardly the bucket 80 is returned to first position and the member 87 lowered so that the leading cocoon will float into place above the bucket as shown in Fig. 2.

As each fresh cocoon is fed into the reeling basin 45 the scraper 205 is automatically withdrawn to avoid the chance of the filament being caught and broken. During the return of the cocoon-transferring bucket 80 to first position the scraper 205 is moved forwardly to receive the filaments drawing upwardly to the reeling mechanism whereby it acts to wipe or scrape the water and foreign matter therefrom. The revolving arms 193 of the gatherer 192 act to engage and break the filament from the new cocoon *c'* as it is fed into place and to twist it about the several other filaments leading upwardly through the spindle 199. After the new filament is joined to the others in this manner it feeds upwardly therewith to the reeling mechanism.

The addition of a new filament to the thread *t* increases its thickness to the required size so that as it draws over the roller 219 it lifts the detector 230 to separate its contact-point 239 from the fixed contact-point 240 whereby to open the circuit to the magnets 185. As the magnets 185 are deenergized they release the armature 181 to allow the member 180 to return to first position.

It will be understood that when a filament breaks or is exhausted the cocoon from which it is supplied, or the larva residue therefrom, drops to the bottom of the basin 45 as indicated in Fig. 4 so that as the gate 57 is opened the circulation of the water causes the spent cocoon *c'* to be washed into the flushing chamber 60 in the manner indicated in Fig. 5. Should the spent cocoon still float in the basin 45 the current will discharge it therefrom in the same manner as the level of the water is lowered. When the gate 57 is again closed the flushing door 62 is opened to permit the water in the chamber 60 to debouch through the opening 52 to carry the waste cocoon *c'* into the return pipe 63 in the manner as illustrated in Fig. 2. As the water flows to the source of supply it passes through a suitable screen, not herein shown, which acts to remove the waste cocoons.

Should the thread *t* break from any cause the stopping mechanism will be actuated to arrest the reeling operation in the manner as next explained. If the thread breaks between the reeling basin 45 and the pulley 212 the tension on the latter is relieved to cause the arm 213 to be raised under the action of its weight 262, see Fig. 8. This has the effect to impinge the rounded end 261 of the arm 260 against the contact-blade 258 to depress the latter whereby to close its contact-point against the fixed contact-point on the blade 259. The electrical circuit is thus closed to energize the magnets 295 to cause them to attract the armature 296 whereby to rock the rod 285. The downwardly extending leg 286 of the rod 285 is thus brought into position above the eccentric disk 287 and engaged thereby whereby to lift the reel-carrying arms 265 as shown in Fig. 8 to free the drive-wheel 270 from the driving drum 271. In this manner the rotation of the reel 268 is arrested and the winding operation stopped. As the arms 265 are swung upwardly the latching member 288 engages with the upper 75

edge of the detent-plate 290 to prevent the return of the arms until it is desired to restart the winding operation. The upward movement of the arms 265 permits the electrical switch 300 to rock to the position indicated in Fig. 8 whereby to open the main circuit 305 which supplies current to the contact-blades of the detector device 230. As a result the flow of the current is interrupted so that the detector device will not act to feed any cocoons into the reeling basin 45 while the reeling means is inoperative.

It will be observed from the foregoing that the present invention provides a highly efficient machine for reeling silk directly from cocoons. The reeling units may be compactly arranged in gang form along a common support requiring a minimum of floor space and operated from a common source of power.

The machine is entirely automatic in operation, requiring practically no attention on the part of the operator except to occasionally replenish the supply of reserve cocoons. Thus the operator is able to tend a greater number of units and the cost of reeling is reduced to a minimum.

The machine operates with great precision in maintaining a uniform thickness in the thread being reeled and consequently the quality of the product is greatly improved.

While I have herein illustrated and described a preferred form of construction of the machine, it is to be understood that various changes may be made in the structure and arrangement of its parts without departing from the spirit or scope of the invention. Therefore, without limiting myself in this respect, I claim:

1. In a silk-reeling machine, the combination of a basin for liquid, means for reeling a thread of predetermined size from filaments delivering from cocoons floating in the basin, means contacting with opposite sides of the thread to detect a reduction in the thickness thereof, means actuated therefrom upon indication of such reduction in thickness of the thread below the predetermined size to feed a fresh cocoon into the reeling basin, and means for attaching the filament from the fresh cocoon to the other filaments feeding to the thread.

2. In a silk-reeling machine, the combination of a basin for liquid, means for reeling a thread of predetermined size from filaments drawing off from a plurality of cocoons floating in the basin, a detector contacting with opposite sides of the thread being reeled to indicate variations in the size thereof, means for feeding fresh cocoons into the basin, and means actuated by the detector upon indication of a reduction in thickness of the thread below the predetermined size to operate the cocoon-feeding means.

3. In a silk-reeling machine, the combination of a basin for liquid, means for reeling a thread of predetermined size from filaments unwinding from a plurality of cocoons floating in the basin, a detector contacting with opposite sides of the thread for measuring the thickness of the thread, means for feeding fresh cocoons into the basin, electrically-controlled means for operating the feeding means, an electrical circuit therefor, and means actuated by the detector upon indication of a reduction in thickness of the thread below the predetermined size to close the circuit to energize the cocoon-feeding means.

4. In a silk-reeling machine, the combination of a basin for liquid, means for reeling a thread of predetermined size from filaments delivering from a plurality of cocoons in the basin, means

for feeding fresh cocoons into the basin, a detector in contact with opposite sides of the thread being reeled and actuated when the diameter of the thread is reduced below the predetermined size, and means actuated by the detector upon indication of a reduction in the diameter of the thread below the predetermined size to energize the cocoon-feeding means. 5

5. In a silk-reeling machine, the combination of a basin for liquid, means for reeling a thread of predetermined size from filaments delivering from a plurality of cocoons floating in the basin, means for feeding fresh cocoons into the basin, electrically energized means for operating the cocoon-feeding means, an electrical circuit therefor, a detector in contact with opposite sides of the thread being reeled and actuated upon indication of a reduction in thickness of the thread below the predetermined size, and means actuated by said detector to close the electrical circuit 10 to energize the cocoon-feeding means.

6. In a silk-reeling machine, the combination of a basin for liquid, means for reeling a thread of predetermined size from filaments delivering from a plurality of cocoons in the basin, means for feeding fresh cocoons into the basin, power-operated means for actuating the feeding means, detent-means for normally maintaining the power-operated means inactive, and means contacting with opposite sides of the thread being 15 reeled and actuated when the thickness of the thread is reduced below the predetermined size to release the detent-means to cause actuation of the cocoon-feeding means.

7. In a silk-reeling machine, the combination of a basin for liquid, means for reeling a thread of predetermined size from filaments delivering from a plurality of cocoons floating in the basin, means for feeding fresh cocoons into the basin, power-operated means for actuating the cocoon-feeding means, a clutch for connecting the power-operated means with the actuating means, detent-means for normally maintaining the clutch inoperative, and means contacting with opposite 25 sides of the thread being reeled and actuated when the thickness of the thread is reduced below the predetermined size to operate the detent-means to release the clutch to operate the cocoon-feeding means. 30

8. In a silk-reeling machine, the combination of a basin for liquid, means for reeling a thread of predetermined size from filaments delivering from a plurality of cocoons floating in the basin, means for feeding fresh cocoons into the basin, 35 a shaft for operating the feeding means, continuously driven means for rotating the shaft, a friction clutch for connecting the rotating means with the shaft, means for normally maintaining the clutch inoperative, and a detector engaging opposite sides of the thread being reeled and actuated upon reduction in the diameter of the 40 thread below the predetermined size to connect the clutch to operate the cocoon-feeding means.

9. In a silk-reeling machine, the combination of a basin for liquid, means for reeling a thread of predetermined size from filaments delivering from a plurality of cocoons floating in the basin, means to feed fresh cocoons into the basin, a cam for operating the feeding means, means for 45 rotating the cam, a clutch for connecting the rotating means with the cam, detent-means for maintaining the clutch disconnected, electrically-controlled means for releasing the detent-means, an electrical circuit therefor, and means contacting with opposite sides of the thread being 50

rotating means with the cam, detent-means for maintaining the clutch disconnected, electrically-controlled means for releasing the detent-means, an electrical circuit therefor, and means contacting with opposite sides of the thread being 55

reeled and actuated upon reduction in the thickness of the thread below the predetermined size to close the circuit to the electrically-controlled means.

- 5 10. In a silk-reeling machine, the combination of a basin for liquid, means for reeling filaments from a plurality of cocoons floating in the basin, means for feeding fresh cocoons into the basin, means for operating the feeding means, a clutch 10 for controlling the operation of the feeding means, a lever for maintaining the clutch inoperative, a knock-off lever for releasing the clutch-lever, a toothed wheel for actuating the knock-off lever, an electromagnet for engaging 15 the knock-off lever with the toothed wheel, and means actuated upon breakage or exhaustion of one of the filaments to energize the electromagnet.
- 20 11. In a silk-reeling machine, the combination of a basin for liquid, means for reeling a thread composed of filaments from cocoons floating in the basin, electrically-controlled means for supplying fresh cocoons to the basin, an electrical circuit for said means, means for energizing the 25 electrical means upon breakage or exhaustion of a filament feeding to the reeling means, means for arresting the reeling operation upon breakage of the thread or exhaustion of its supply, and means actuated by the arrestment of the reeling 30 operation to open the circuit to the electrically-controlled means.

35 12. In a silk-reeling machine, the combination of a basin for liquid, means for reeling a thread composed of filaments from cocoons floating in the basin, means for feeding fresh cocoons into the basin, electrically-controlled means for actuating the feeding means, an electrical circuit for said means, a detector operative to close said circuit upon breakage or exhaustion of a filament 40 leading to the thread, electrically-controlled means for arresting the reeling operation upon breakage or exhaustion of the thread, and means actuated therefrom to open the circuit for the cocoon-feeding controlling means.

45 13. In a silk-reeling machine, the combination of a basin for liquid, means for reeling filaments from cocoons floating in the basin, means for circulating liquid through the basin, a gate for controlling the circulation of the liquid through the 50 basin, and means for intermittently opening the gate to discharge spent cocoons from the basin.

55 14. In a silk-reeling machine, the combination of a basin for liquid, means for reeling filaments from cocoons floating in the basin, means for circulating liquid through the reeling basin, a flushing chamber connected with the reeling basin, a gate separating the flushing chamber from the reeling basin, and means for periodically opening the gate to discharge spent cocoons 60 from the reeling basin into the flushing chamber.

65 15. In a silk-reeling machine, the combination of a basin for liquid, means for reeling filaments from cocoons floating in the basin, means for circulating liquid through the reeling basin, a flushing chamber connected with the reeling basin, a gate between the reeling basin and flushing chamber, means for periodically opening the gate to discharge spent cocoons from the reeling basin into the flushing chamber, a door in the 70 flushing chamber, and means for periodically opening the door to drain the flushing chamber.

75 16. In a silk-reeling machine, the combination of a basin for liquid, means for reeling filaments from cocoons floating in the basin, means for circulating liquid through the basin, a flushing

chamber connected with the basin, a gate between the reeling basin and flushing chamber, said gate formed with restricted openings to permit the liquid to flow therethrough to maintain a predetermined level in the reeling basin, and means for periodically opening the gate to cause the flow of liquid to discharge spent cocoons from the reeling basin into the flushing chamber.

80 17. In a silk-reeling machine, the combination of a basin for liquid, means for reeling filaments from cocoons floating in the basin, means for circulating liquid through the basin, a flushing chamber connected to the basin, a gate between the reeling basin and flushing chamber, means for periodically opening the gate to discharge spent cocoons from the reeling basin into the flushing chamber, an overflow conduit leading from the flushing chamber, a door in the bottom of the flushing chamber, and means for periodically opening the door after the closing of the 20 gate.

85 18. In a silk-reeling machine, the combination of a basin for liquid, means for reeling filaments from cocoons floating in the basin, means for circulating liquid through the basin, a flushing 25 chamber, means for debouching the liquid from the reeling basin into the flushing chamber, and means operative thereafter for exhausting the liquid from the flushing chamber.

90 19. In a silk-reeling machine, the combination of a basin for liquid, means for reeling filaments from cocoons floating in the basin, means for supplying liquid to the basin, a gate, means for periodically opening the gate to exhaust the liquid from the basin, and manually-operable 35 means for arresting the operation of the gate-opening means.

95 20. In a silk-reeling machine, the combination of a basin for liquid, means for reeling filaments from cocoons floating in the basin, a compartment for reserve cocoons, a raceway leading from the reserve compartment to the reeling basin, means at the end of the raceway for feeding the foremost cocoon into the reeling basin, means for actuating the feeding means upon breakage 45 or exhaustion of one of the filaments being reeled, and means for rocking the raceway to advance the cocoons to the feeding means.

100 21. In a silk-reeling machine, the combination of a basin for liquid, means for reeling filaments from cocoons floating in the basin, a raceway leading to the basin, means for feeding the foremost cocoon from the raceway into the reeling basin, means for oscillating the raceway, and means for operating the cocoon-feeding means 55 from the oscillation of the raceway.

105 22. In a silk-reeling machine, the combination of a basin for liquid, means for reeling filaments from cocoons floating in the basin, a raceway leading to the basin, a rockable feeding bucket 60 at the end of the raceway, and means to oscillate the raceway to rock the feeding bucket to transfer cocoons into the basin.

110 23. In a silk-reeling machine, the combination of a basin for liquid, means for reeling filaments from cocoons floating in the basin, a raceway leading to the reeling basin, an agitator in said raceway, and means for oscillating the agitator to prevent the cocoons from clogging in the raceway.

115 24. In a silk-reeling machine, the combination of a basin for liquid, means for reeling filaments from cocoons floating in the basin, a raceway leading to the reeling basin, means for oscillating the raceway, a pivoted agitator in the 70

raceway, and means operative by the oscillation of the raceway to actuate the agitator to prevent the cocoons from clogging the raceway.

25. In a silk-reeling machine, the combination 5 of a basin for liquid, means for reeling filaments from cocoons floating in the basin, means for feeding fresh cocoons into the reeling basin, means for connecting the filament from a fresh 10 cocoon to the filaments being reeled, scraper means through which the filaments draw, and means for withdrawing the scraper means from operative position during the transfer of a fresh 15 cocoon into the reeling basin.

26. In a silk-reeling machine, the combination 15 of a basin for liquid, means for reeling filaments from cocoons floating in the basin, means for feeding fresh cocoons into the reeling basin, means engaging the reeling filaments to scrape the liquid therefrom, and means for releasing said 20 scraping means from the filaments during the transfer of a fresh cocoon into the reeling basin.

27. In a silk-reeling machine, the combination 25 of a basin for liquid, means for reeling a thread of predetermined size from filaments unwinding from cocoons floating in the basin, means contacting with opposite sides of the thread and movable diametrically thereof under variations in the size of the thread, means for feeding fresh 30 cocoons into the basin, and means actuated by the movement of the contact-means to control the operation of the cocoon-feeding means.

28. In a silk-reeling machine, the combination 35 of a basin for liquid, means for reeling a thread of predetermined size from filaments unwinding from cocoons in the basin, a fixed element across which the reeling thread feeds, a detector opposed to the fixed element to bear against the thread and adapted to be moved upon the occurrence of variations in the thickness thereof, 40 means for feeding fresh cocoons into the basin, and means actuated by the movement of the detector upon variations in thickness of the thread

to control the operation of the cocoon-feeding means.

29. In a silk-reeling machine, the combination 5 of a basin, means for reeling a thread of predetermined size from filaments unwinding from cocoons in the basin, detector means contacting with opposite sides of the thread being reeled and relatively movable under variations in the size thereof, means for feeding fresh cocoons into the basin, electrically-energized means for 10 operating the cocoon-feeding means, a normally open circuit, and means actuated by the relative movement of the detector means to close the circuit to energize said operating means.

30. In a silk-reeling machine, the combination 15 of a plurality of cocoons, means for reeling a thread composed of filaments from said plurality of cocoons, electrically-controlled means for supplying fresh cocoons to said plurality of cocoons, an electrical circuit for said means, means for 20 energizing the electrically-controlled means upon breakage or exhaustion of a filament feeding to the reeling means, means for arresting the reeling operation upon breakage of the thread or exhaustion of its supply, and means actuated on 25 the arrestment of the reeling operation to open the circuit to the electrically-controlled means.

31. In a silk-reeling machine, the combination 30 of a plurality of cocoons, means for reeling a thread composed of filaments from said plurality of cocoons, means for supplying fresh cocoons to said plurality of cocoons, electrically-controlled means for actuating the supply means, an electrical circuit for said means, a detector operative to close said circuit upon breakage or exhaustion 35 of a filament leading to the thread, electrically-controlled means for arresting the reeling operation upon breakage or exhaustion of the thread, and means actuated therefrom to open the circuit 40 for the cocoon-supply controlling means.

GUSTAF SIGFRID BECKMAN.
